UNITED STATES PATENT OFFICE.

RICHARD D. MILLHOUSE, OF STANFORD, MONTANA.

DRAFT-TONGUE.

1,234,374.

Specification of Letters Patent. Patented July 24, 1917.

Application filed February 28, 1917. Serial No. 151,520.

To all whom it may concern:

Be it known that I, RICHARD D. MILLHOUSE, a citizen of the United States, residing at Stanford, in the county of Fergus 5 and State of Montana, have invented certain new and useful Improvements in Draft Tongues, of which the following is a specification, reference being had to the accompanying drawings.

10 This invention relates to certain improvements in draft tongues and it is an object of the invention to provide a device of this general character having novel and improved means whereby a neck yoke may 15 be readily adjusted longitudinally thereof as the requirements of practice may dictate.

It is also an object of the invention to provide a novel and improved draft tongue including an extension and wherein said extension 20 is provided with a hold-back mounted for swinging movement and having yieldable means coacting therewith for normally holding the same in operative position.

The invention consists in the details of 25 construction and in the combination and arrangement of the several parts of my improved tongue whereby certain important advantages are attained and the device is rendered simpler, less expensive and otherwise 30 more convenient and advantageous for use, all as will be hereinafter more fully set forth.

The novel features of the invention will 35 hereinafter be definitely claimed.

35 In order that my invention may be the better understood, I will now proceed to describe the same with reference to the accompanying drawings, wherein—

Figure 1 is a view in elevation of the 40 outer end portion of a draft tongue and illustrating an embodiment of my invention;

Fig. 2 is a view partly in side elevation and partly in section of the device as herein embodied; and

45 Fig. 3 is a view in top plan of the device as herein included.

As disclosed in the accompanying drawings, T denotes a draft tongue of a conventional type and which has secured thereto 50 the iron 1 provided with the depending hold-back stop 2 which is adapted to have coacting therewith a neck yoke in a conventional manner and which hold-back stop is particularly adapted for use when a two-horse 55 evener is employed in connection with the tongue T.

E denotes an extension substantially U-shaped in form and having the free end portions of its side members overlying the sides of the tongue T at the outer end of said tongue and anchored thereto, as indicated at 60 3, in any conventional manner. The extension E terminates a predetermined distance in advance of the outer end of the tongue T and is in substantially the same horizontal 65 plane.

The side members of the extension E at a point in close proximity to the outer end of the tongue T have engaged therewith the member 4 intersecting the space between 70 said side members and with which is pivotally engaged an end portion of an arm 5. The arm 5 extends forwardly of the extension E and terminates in a depending extension 6 substantially perpendicular to the 75 arm 5 and which serves as a second hold-back stop and with which the neck yoke is adapted to be operatively engaged when a four-horse evener or the like is employed in connection with a draft tongue T. 80

The outer end portion of the arm 5 overlies the stop 7 herein disclosed as a conventional bolt supported by the side arms of the extension E and intersecting the space therebetween. The arm 5 is normally maintained 85 in contact with the stop 7 through the medium of the flat spring member 8 having one end portion anchored, as at 9, to the outer extremity of the tongue T while the opposite or free end portion of said spring 90 member 8 bears upon the upper face of the arm 5 adjacent its outer end.

It is thought to be self-evident that in the event the neck yoke is employed in connection with the hold-back stop as afforded by 95 the extension 6 of the arm 5, it is only necessary to elevate the arm 5 sufficiently to permit the neck yoke to be moved back to the stop 2 and which adjustment is required when a two-horse evener is substituted for 100 a four-horse evener.

As the character of the two-horse evener or the four-horse evener forms no particular part of my present invention and as the use thereof is believed to be self-evident, a 105 detail description or illustration thereof has been omitted.

From the foregoing description, it is thought to be obvious that a draft tongue constructed in accordance with my invention is of an extremely simple and comparatively inexpensive nature and is particu-

larly well adapted for use by reason of the convenience and facility with which it may be assembled, and it will also be obvious that my invention is susceptible of some change and modification without material departure from the principles and spirit thereof and for this reason I do not wish to be understood as limiting myself to the precise arrangement and formation of the several parts herein shown in carrying out my invention in practice, except as hereinafter claimed.

I claim:

In combination with a wagon tongue provided with a hold-back stop, a substantially U-shaped extension secured to the outer ex-

tremity of the tongue, a supplemental hold-back stop pivotally supported by the extension, a member carried by the extension for limiting the movement of the supplemental hold-back stop in one direction, and a spring member coacting with the supplemental hold-back stop for normally holding the same in contact with the limiting member.

25

In testimony whereof I hereunto affix my signature in the presence of two witnesses.

RICHARD D. MILLHOUSE.

Witnesses:

JAMES J. MURPHY,
GORDON STEPHENSON.
